Primary Examiner — Cynthia Ramirez*Assistant Examiner* — Tamara L Hahn(74) Attorney, Agent, or Firm — Xia Li(57) CLAIM

The ornamental design for a tent cart, as shown and described.

DESCRIPTION

FIG. 1 is a perspective view of a tent cart showing my new design;

FIG. 2 is second perspective view thereof;

FIG. 3 is third perspective view thereof;

FIG. 4 is fourth perspective view thereof;

FIG. 5 is a front view thereof;

FIG. 6 is a back view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged portion taken from line 11 in FIG. 1;

FIG. 12 is an enlarged portion taken from line 12 in FIG. 2; and,

FIG. 13 is an enlarged portion taken from line 13 in FIG. 3. The dot-dash broken lines in the drawings depict enlarged portions of the tent cart that form no part of the claimed design.
